UNITED STATES PATENT OFFICE

FOREST D. GOODY, OF DENVER, COLORADO

AUTOMATICALLY OPERATING GOLD PLACER GRAVEL CONCENTRATING AND GOLD SAVING DEVICE

Application filed January 7, 1930. Serial No. 419,042.

My invention relates to a new automatically operating gold placer-gravel concentrating and gold saving device, and the objects of my invention are:

5 First, to provide a combined placer gravel concentrating V shaped hopper, and a gold saving device, the hopper of which automatically guides placer gravel fed into it by hand shoveling, or by machinery and 10 placer gravel dredging and mining machines, so that the gold bearing gravel is concentrated into a narrow screen covered open bottom portion, from its wide open top portion, and that is so constructed that the gold 15 in the gravel is separated from the gravel in the hopper that is larger than the mesh of its screens and falls through the meshes of its screens into the gold saving sluice box or boxes below it, and that at the same time 20 also separates and screens the gold in the gravel as the gravel runs down the opposite downwardly and inwardly converging sides of the hopper and guides the gold thus separated from the gravel down into the 25 sluice box below it, the hopper separating the gold in the gravel at the time the gravel is traveling through it, in addition to separating the large rocks and all of the coarse pebbles in the placer gravel that is larger 30 than the mesh of screens used in the hopper.

Second, to provide a simple and inexpensive hopper member for sluice boxes that is especially adapted to have placer gravel shoveled into it by one of two placer miners 35 standing on one or opposite sides of it and the sluice box members.

I attain these objects by the mechanism illustrated in the accompanying drawings in which:

40 Fig. 1 is a side view of the improved placer gravel concentrating and gold saving apparatus, including a motor operated pump for supplying wash water to the hopper which receives the placer material.

45 Fig. 2 is a plan view thereof.

Fig. 3 is an enlarged vertical longitudinal sectional view of the improved form of feed hopper to which the placer material is supplied.

50 Fig. 4 is a plan view thereof, a portion of

the bottom screen being removed and the side screens being omitted.

Fig. 5 is a vertical transverse sectional view of the hopper.

Fig. 6 is a rear end view of a portion of 55 the apparatus, showing more particularly the manner of adjustably supporting the rear end of the hopper.

Fig. 7 is a detail front view, showing adjustable extensions for the front legs of the 60 supporting frame of the apparatus.

Fig. 8 is a vertical transverse sectional view of a modified form of the feed hopper, the same being made of sheet metal, and having a curved bottom and curved bottom 65 screen, and

Fig. 9 is a transverse sectional view through the sluice box.

Similar letters of reference refer to similar parts throughout the several views. 70

Referring to the drawings, the numeral 1 designates a sluice-box supporting frame, which is so designed that the sluice-box or boxes that are supported by it can be raised or lowered and inclined at any predetermined 75 downward angle to allow placer gravel and sand and water to run through it, at the speed that is found to best allow the gold to settle out of the gravel and sand into the gold catching fabric in the bottom of the sluice-box, or boxes, as this sluice-box supporting frame is made wide enough to support one wide sluice-box or one narrow sluice-box or two sluice-boxes, side by side.

This sluice-box supporting frame is constructed of strips of light dimension lumber or light weight structural iron or steel. The construction consists of the vertical standards 2, of which there are four, and the longitudinal connecting pieces 3, along the opposite 80 sides of the vertical standards 2, and the transverse end pieces 4 and 4A, upon which the sluice-box or boxes 5, rest. All of these pieces of the supporting frame are detachably secured together by bolts and nuts so that 85 they can be quickly taken apart and stacked together in a bundle for transportation in an auto-truck or on a wagon of any kind, but when assembled together in sluice-box supporting condition their lower ends rest on the 90 100

ground, or if preferred on a flat rock, or a plank, no special foundation being needed for them.

The standards are provided with vertical slots 6, and the opposite ends of the transverse pieces 3, are provided with bolts 7, which extend into and through these slots, and their ends are threaded, and butterfly nuts 8, are threaded to them, and arranged to clamp the standards to the opposite ends of the transverse sluice-box supporting pieces of the sluice-box supporting frame. As the sluice-box rests on these transverse pieces at its opposite end portions, and as it is inclined downwardly from the end of it into which the placer ground is fed, these transverse pieces are raised or lowered in the standards until the sluice-box stands at the desired inclination, and they are then clamped tightly to the standards at that point in their height.

One or two sluice-boxes 5, are placed on the transverse pieces 4 and 4A, and they may be secured to them if desired, but they do not need to be, and it is only necessary to prevent it from slipping downwardly on them, and this may be accomplished by any suitable means, such as by securing a cleat of wood 9, on the bottom of the sluice-box up against the cross pieces 4 and 4A.

The sluice-box as I illustrate it in my present invention is stationary, that is, it is preferably not vibrated or reciprocated, but it may be if desired, by attaching to it and arranging it as shown in my Patent No. 1,752,169, granted March 23, 1930, for an automatically operating apparatus for catching and concentrating gold, etc.

The sluice-box or boxes I preferably use are narrow boxes as used in my present invention. They are preferably made of one inch planed lumber, and are preferably about twelve inches wide on the bottom 10, and are about ten inches wide inside of the opposite sides 11, of the sluice-boxes, which are about four inches high, above the floor 12, of the bottom inside the sluice-box. The upper end 13, of the sluice-box is closed by a cross piece of board 14, the construction being similar to that illustrated in my Patent No. 1,588,102, issued to me June 8, 1926.

Inside of the sluice-box I place down on and against the bottom of it any suitable gold-catching fabric or material, or fabrics and materials 15, in a single layer or in more than one layer, and on top of the gold-catching fabric I place a screen 16, which may be a cross wire screen, or a punched plate screen, or any other kind or type of screen that will act to arrest and check the downward flowing movement of the gold particles in the gravel and sand as they flow through the sluice-box, different types of which are illustrated in my above mentioned Patent No. 1,752,169.

The screen, or screens, as there may be one or two, or more, on top of each other, as

shown in my above mentioned patent, although I preferably use only one in my present invention, is pressed down against the gold-catching fabric tight enough to make a bearing contact against its gold-catching surface. The screen is held in that position by narrow wooden cleats, preferably in the form of half round strips 16A, which are secured to the opposite sides of the sluice-box by small nails that are easily and quickly withdrawn so as to easily and quickly remove the cleats when it is desired to remove the screen and the gold-catching fabric in the bottom of the sluice-box.

In my present invention the placer gravel and sand and water feed into the upper end 13, of the sluice-box 5, through a hopper 19, which rests at its lower end by means of a skid 21, and is secured against accidental displacement to the upper end of the sluice-box while the upper end of the hopper is adjustably secured to the upper ends of the end standards by any suitable means, to be raised or lowered to get different downward placer gravel discharging angles. Preferably, however, I secure the hopper to cross piece 17, which is secured to the standards by an iron strap 18 of U-shape, which is provided with apertures 18 at short distances apart, and the strap is secured at its center to the outside under closed end of the hopper and its ends are placed loosely and removably over pins 19, which are secured to the cross piece 17, so that the upper end of the hopper can be raised and lowered by the operator to give to the bottom of the hopper a discharging angle for the gravel which is too coarse to pass through the mesh of the screens used in the bottom, and on the opposite sides of it, which will best suit the sized rocks and pebbles in the gravel he is to run through it. Because my present gold-saving device is a portable machine, one miner has small sized pebble gravel to run through it and another miner has large pebble and rock gravel to run through it.

While the hopper can be made any practical length, I preferably make it about three ft. long on its bottom and three and a half ft. long on its top edges, by about eighteen inches high at its upper end and by about twenty inches wide at its upper open end inside its opposite sides and sloping downwardly and inwardly to a closed bottom portion 19A, of preferably about four inches wide inside at its discharge end, and about six inches wide at the head end of the hopper, as the hopper is made wider at its gravel receiving end and tapers smaller to its discharge end. The hopper, as illustrated in Figures 1 and 2, is made of wooden boards, but it may be made of sheet iron or steel as shown in Figure 8. It is provided with a hood member 20, which extends high enough above its side edges and forwardly far enough to receive

the placer gravel and sand that is shoveled into it without its flying over the rear side and the rear end cross member 21A of the hopper.

5 A screen 22, is removably placed in the bottom of the hopper and its opposite side edges rest on projecting cleat members 23, which in the wooden construction preferably consist of half-round, wooden strips which are 10 nailed or otherwise secured to the opposite sides of the hopper.

The opposite sides of the hopper are also covered with screens 24, which extend downward at a more inward angle so that at their 15 lower edges which extend to the opposite side edges of the bottom screen they stand at about an inch away from the sides of the hopper.

Thus a tapering and narrowing space for the placer gravel and sand and gold which flows 20 through each side screen is formed from the upper edges of these screens to their bottom edges where they are secured against half round strips of wood which rest on the half round strips 23, on which the screen 22 rests.

25 The strips 24 A, are secured by any suitable means against the sides of the hopper, and the gravel and sand and the gold and other metals which pass through these side screens collect on top of these half round strips of wood,

30 and in order that the gravel and sand and the gold and other metals may move down past them onto the bottom portion of the hopper. I provide the front sides of both of the strips 23 and 24 A with deep grooves

35 24 B, that extend down through them, and while these grooves 24 B, can be made to extend down through these two half round strips in a straight line, I preferably arrange them at a forwardly and downwardly in-

40 clinched angle as shown in Figure 4. Consequently these side screens collect gold and other metals and it is conveyed from their lower ends down into the bottom space 24 C, of the hopper onto its floor 24 D, independ-

45 ently of the screen 22, in the bottom of the hopper, and the pebbles and the rocks of the gravel which are too coarse to pass through the screens in the bottom and sides of the hopper are washed out of the lower end of

50 the hopper into a chute 25, which is removably secured to its end by any suitable means, which extends over one side of the sluice-box and conveys and discharges the over-size gravel as worked over waste gravel; also the

55 screened gravel carrying the gold and other metals which flows from the hopper into the sluice-box is washed through the sluice-box and in flowing through it the gold and platinum and other metals sink down through it

60 and through the meshes of the screen on top of it into the fabric in the bottom of the sluice-box and is saved by being concentrated therein. After the fabric is well filled with gold and other metals the fabric is removed

65 and the gold and other metals are washed out

of it. It is then replaced in the bottom of the sluice-box. The other metals most generally found in placer gravel are platinum which occurs in its native state and is a trifle heavier than gold and easily sinks into and is held by the fabric, and also black sand which contains iron, which is not as heavy as gold but is caught in the fabric. It is sometimes worthless but occasionally carries a little gold. Prospectors using my gold saving device can separate the gold and platinum from the black sand in the fabric after washing them out of the fabric by hand panning. The gold can also be recovered by itself and the platinum by itself, separate from the gold and from the black sand by chemical or smelting processes.

The screens that I use in the bottom and on the sides of the hopper are cross wire or punched plate screens, and they are not what are known as grizzly screens as this character of screen will not work satisfactorily over my sluice-box. The cross wire or punched screen that I use may be of any size mesh from the finest that it is practical to use for screening placer gravel, to a mesh as large as one and a half inches, the size of the mesh or holes in the screen depending on the fineness or the coarseness of the gold in the gravel; for instance, for gravel consisting of small pebbles and sand containing fine gold that will pass through a sixty mesh screen and contain gold as fine as flour. I would use a screen preferably of a quarter inch mesh, either a cross wire screen or a punched plate, of which there are several kinds illustrated in my patent above referred to, but a little finer or coarser screen can be used if conditions require it.

At the present time I am using a one inch mesh screen in one of these machines that I have set up and am treating placer gravel, that is, coarse gravel containing quite large rocks on a placer bar that contains medium coarse gold that is of a flat thin flakey character, in which there is only a little gold.

And at another placer bar I am using a number one-half inch mesh screen in one of these machines extracting gold from gravel and sand that is very much finer than the coarse gravel just mentioned, and extracting gold from it that is fine gold some of it being very fine down to flour gold and with only occasionally a few small coarse pieces of nugget form of gold in it.

If, however, the placer gravel contains gold, some of which will go through a quarter inch screen but will not go through a three-sixteenth inch screen, I would prefer to use a screen of one-half inch mesh. Then again if the placer gravel contains nuggets up to about one-half to three-quarters inch in size occasionally I would use a screen of one inch to one and a half inch mesh, depending on the size of the rocks in the gravel.

At the lower discharge end of the hopper I place a down-spout 25A, adjoining the skid 21, which rests on the upper edges of the side boards of the sluice-box, and all of 5 the gravel and sand and platinum and gold and other metals that pass down through the holes or meshes of the screens with the water drop down onto this bottom portion 24C of the hopper and run down it into the down- 10 spout and through it into the head end of the sluice-box.

A water supply under sufficient pressure to disintegrate and to force the firmly pressed together sand, mud and fine pebbles 15 and to wash off the larger pebbles and the rocks that are in the gravel, and directed to strike the screen in the bottom of the hopper, flows with pressure up along it and against the back head end portion of the hopper, and 20 thus against the gravel as it is shoveled into the hopper up under the hood, or discharged there from dredging machinery.

And while my invention contemplates any 25 kind or character of water pressure supply for washing the gravel thoroughly while it is in the hopper and for washing it out of the hopper, I preferably provide a small power and a light-weight portable water pumping plant, with the water discharging 30 nozzles I prefer to use to wash the gravel and to furnish the water to wash the screened gravel and sand through the sluice-box after it has been screened from the coarse gravel and rocks in the hopper.

35 The pumping and water supplying apparatus I preferably provide with my gold saving device consists of a gasoline engine 26, with its electrical equipment and a pump 27, belt connected to and driven by the engine, 40 which is shown adjacent a water provided sump hole 28A, and the water delivery pipe line 29, and the nozzles 30 and 31, I preferably use two nozzles and in order to secure the required pressure I preferably use 45 a smaller size pipe than the water conveying pipe for the nozzles 30 and 31, and place the second nozzle under the upper nozzle, as shown, and I preferably place and support the water conveying pipe and the nozzles 50 over the top of the sluice-box and parallel to it, and place the discharge ends of the nozzles at a distance from the center of the bottom of the hopper so that the water as it is discharged from the end of the upper nozzle 55 will strike the bottom screen and also the side screens to the full height of the under side of the hood and the full area of the head end portion of the hopper, so that the lower nozzle will strike the bottom screen 60 of the hopper below where the upper nozzle strikes it, and these two streams of water should have pressure enough to check and hold the gravel back in the hopper and disintegrate it and wash it clean of any gold 65 particles that may be clinging to it. That

part of it smaller than the meshes of the screens is washed through, and the over-size gravel is washed out of the hopper, and in actual, practical use my gold saving device with the water supply under pressure 70 and discharged in the hopper, as illustrated, accomplishes that in a very few seconds of time, after the gravel is shoveled by hand into it, or is discharged into it by dredging machinery. 75

The gasoline engine can be as small as a one and one-half horse power, and the pump can be either a one and a one-half inch rotary or centrifugal pump and the weight of it, and the expense of the entire pumping equipment, is small and it is easily transported 80 from one placer to another, or from one part of a placer bar to another part of it.

The oversize discharging chute 25, is made to be changed to discharge over either one 85 side or the other of the sluice-box. It is secured at one end to the screen and a slide block 21 is secured to the front end of the hopper and rests crosswise on top of the side boards of sluice-box and can be quickly 90 changed over from one side of the sluice-box to its opposite side, and the sliding block allows it to be moved outward away from the side of the sluice-box a few inches. This arrangement allows the discharging oversize a larger area in which to spread out as it discharges into a larger pile, or into a conveying apparatus which would convey and discharge it at some distance away from the gold saving device. 95

100 The operation of my automatically operating gold saving device is as follows:

When the water is turned on and is discharging with force into the hopper, either one or two men, standing on either one or 105 both sides of it, can shovel placer gold carrying gravel into the hopper up against its head end and under its hood, as fast as they can, and the water will wash the gold out of it, and from off of its rocks and pebbles, and 110 it will be carried with the fine gravel and water through the screens and will flow with them into the sluice box where it settles down out of the fine gravel and water into the fabric in the bottom of the sluice-box and is saved. 115 The sand and fine pebbles that run through the sluice-box run to waste while the rocks and pebbles of the gravel which are too large to flow through the meshes of the screens 120 flow out of the hopper through the chute, also to waste. If desired the operators can instead of shoveling the placer gravel into the hopper employ drag-line or other machinery to raise it and feed it into the hopper. Two men can, however, shovel from forty to 125 fifty yards of gravel into the hopper in a day where the conditions are favorable for steady work, and from three to four times that many yards if the gravel is fed to it by machinery. 130

My invention is especially adapted for placer miners who desire a machine that can be easily and quickly moved around, and one which is simple in construction and whose 5 vital parts are easily and quickly reached for cleaning and in which the gold it saves is easily and quickly removed from it. While I have illustrated and described the preferred construction and arrangement of my 10 gold saving device I do not wish to be limited to the construction and arrangement shown as changes may be made in it without departing from the spirit of my invention.

Having described my invention what I 15 claim as new and desire to secure by Letters Patent is:

1. A gold saving device of the type having a supporting frame, and gold saving sluice box operatively supported in said frame comprising, in combination a V-shaped hopper suspended at the upper placer gravel receiving end from said frame and having a discharging spout secured on the placer gravel receiving end of the sluice box, said hopper having a 20 closed bottom floor member leading to said spout, a screening member across the bottom portion of said hopper, the screenings from which drop onto the floor of said hopper, said hopper being provided with screens 25 provided with strips on its opposite sides positioned at a sufficient distance from the surface of said side members to allow the screen gravel and gold to flow down between the removable projecting strip members arranged to support the opposite side edges of said cross screen and the lower edges of said side screens; said supporting strips being provided with recesses extending downwards through them to allow the screened gravel 30 and gold to flow down through them onto the floor of said hopper, said grooves being extended down through said screen supporting strips at a forwardly and downwardly inclined angle from the space between the side screens and the sides of the hopper into 35 the space below the bottom cross screen to the floor of the hopper, and a head member at the gravel receiving end portion of said hopper arranged thereon to confine the gravel discharged into it from shovels or dredges 40 against being washed out of it, means including nozzles arranged to discharge water under pressure enough to wash gravel clean and out of said hopper.

3. In apparatus of the character described, the combination with an adjustable support, and a sluice box mounted thereon at an inclination to a horizontal plane; of a trough like hopper at the high end of the sluice box having a skid on the under side of its forward end which rests upon the upper edges of said sluice box, connections on the rear end of said hopper which are adjustably connected to said support, the rear end of said hopper being closed, said hopper being at 50 a greater inclination than the sluice box; a screen supported slightly above the bottom of said hopper, screens secured at their upper edges to the sides of said hopper, and extending down to the bottom screen, said screens being gradually spaced from the sides of the hopper; a chute extending from the lower end of the hopper and above the sluice box to carry off the oversize material; a spout in bottom of said chute at its forward end for discharging the screened product into the sluice box, and pipes for delivering water under pressure to said hopper.

4. In a gold saving apparatus of the character described, a trough-like hopper having a flat narrow bottom of slight depth from which the sides incline outwardly; longitudinal cleats along the inner sides of the hopper a short distance above the bottom thereof, a screen plate supported upon said cleats and longitudinal cleats for holding said screen plate in place, the lower cleats having spaced grooves which are forwardly pitched; screen plates secured along their upper edges to the sides of the hopper and spaced therefrom and extending down past the inner edges of the upper cleats, a discharge spout on the forward bottom portion of the hopper through which the screened material passes and an oversize chute the 130

sitioned at a sufficient distance from the surface of said members to allow the screen gravel and gold to flow down between, removable projecting strip members arranged to support the opposite side edges of said cross screen and the lower edges of said side screens; said supporting strips being provided with recesses extending downwards through them to allow the screened gravel and gold to flow down through them onto the floor of said hopper, said grooves being extended down through said screen supporting strips at a forwardly and downwardly inclined angle from the space between the side screens and the sides of the hopper into 70 the space below the bottom cross screen to the floor of the hopper, and a head member at the gravel receiving end portion of said hopper arranged thereon to confine the gravel discharged into it from shovels or dredges 75 against being washed out of it, means including nozzles arranged to discharge water under pressure enough to wash gravel clean and out of said hopper.

Having described my invention what I 80 claim as new and desire to secure by Letters Patent is:

1. A gold saving device of the type having a supporting frame, and gold saving sluice box operatively supported in said frame comprising, in combination a V-shaped hopper suspended at the upper placer gravel receiving end from said frame and having a discharging spout secured on the placer gravel receiving end of the sluice box, said hopper having a 20 closed bottom floor member leading to said spout, a screening member across the bottom portion of said hopper, the screenings from which drop onto the floor of said hopper, said hopper being provided with screens 25 provided with strips on its opposite sides positioned at a sufficient distance from the surface of said side members to allow the screen gravel and gold to flow down between the removable projecting strip members arranged to support the opposite side edges of said cross screen and the lower edges of said side screens; said supporting strips being provided with recesses extending downwards through them to allow the screened gravel 30 and gold to flow down through them onto the floor of said hopper, said grooves being extended down through said screen supporting strips at a forwardly and downwardly inclined angle from the space between the side screens and the sides of the hopper into 35 the space below the bottom cross screen to the floor of the hopper, and a head member at the gravel receiving end portion of said hopper arranged thereon to confine the gravel discharged into it from shovels or dredges 40 against being washed out of it, means including nozzles arranged to discharge water under pressure enough to wash gravel clean and out of said hopper.

3. In apparatus of the character described, the combination with an adjustable support, and a sluice box mounted thereon at an inclination to a horizontal plane; of a trough like hopper at the high end of the sluice box having a skid on the under side of its forward end which rests upon the upper edges of said sluice box, connections on the rear end of said hopper which are adjustably connected to said support, the rear end of said hopper being closed, said hopper being at 50 a greater inclination than the sluice box; a screen supported slightly above the bottom of said hopper, screens secured at their upper edges to the sides of said hopper, and extending down to the bottom screen, said screens being gradually spaced from the sides of the hopper; a chute extending from the lower end of the hopper and above the sluice box to carry off the oversize material; a spout in bottom of said chute at its forward end for discharging the screened product into the sluice box, and pipes for delivering water under pressure to said hopper.

4. In a gold saving apparatus of the character described, a trough-like hopper having a flat narrow bottom of slight depth from which the sides incline outwardly; longitudinal cleats along the inner sides of the hopper a short distance above the bottom thereof, a screen plate supported upon said cleats and longitudinal cleats for holding said screen plate in place, the lower cleats having spaced grooves which are forwardly pitched; screen plates secured along their upper edges to the sides of the hopper and spaced therefrom and extending down past the inner edges of the upper cleats, a discharge spout on the forward bottom portion of the hopper through which the screened material passes and an oversize chute the 130

sitioned at a sufficient distance from the surface of said members to allow the screen gravel and gold to flow down between, removable projecting strip members arranged to support the opposite side edges of said cross screen and the lower edges of said side screens; said supporting strips being provided with recesses extending downwards through them to allow the screened gravel and gold to flow down through them onto the floor of said hopper, said grooves being extended down through said screen supporting strips at a forwardly and downwardly inclined angle from the space between the side screens and the sides of the hopper into 70 the space below the bottom cross screen to the floor of the hopper, and a head member at the gravel receiving end portion of said hopper arranged thereon to confine the gravel discharged into it from shovels or dredges 75 against being washed out of it, means including nozzles arranged to discharge water under pressure enough to wash gravel clean and out of said hopper.

Having described my invention what I 80 claim as new and desire to secure by Letters Patent is:

1. A gold saving device of the type having a supporting frame, and gold saving sluice box operatively supported in said frame comprising, in combination a V-shaped hopper suspended at the upper placer gravel receiving end from said frame and having a discharging spout, the hopper having a closed bottom floor member leading to said spout, a screening member across the bottom portion of said hopper, the screenings from which drop onto the floor of said hopper, said hopper being provided with screens 20 on its opposite sides, po-

rear end of which extends beneath and is secured to the bottom screen.

5. A gold saving device of the type having a supporting frame, and a gold saving sluice box operatively supported comprising in combination a V-shaped downwardly inclined hopper, vertically adjustable in said supporting frame, said hopper sloping downward sharply and having a short down 10 spout on its underneath side; the hopper having a floor member formed of a plate screen placed at a short distance above its bottom floor member; said hopper also being provided on its V-shaped sides with screens positioned

15

at short distance from the sides of the hopper to form a space between the side screens and the sides of the hopper, whereby the screened gold and gravel passing through the meshes of the side screens will flow down along the sides of the V-shaped hopper and with apertures extending down by the screened floor member of said hopper adapted to allow the gold moving down the sides of the hopper to flow thru its bottom floor portion, thus allowing it to flow from the bottom floor portion of the hopper thru its down spout.

In testimony whereof, I affix my signature.
